Des. 235,614
Patented July 1, 1975

235,614

PNEUMATIC SANDER

James O. Taylor, Lantana, Fla., assignor to Florida
Pneumatic Manufacturing Corp., Boynton Beach, Fla.

Filed Nov. 6, 1973, Ser. No. 413,397

Term of patent 14 years

Int. Cl. D8—05

U.S. Cl. D8—62

FIG. 1

FIG. 2

FIG. 3

FIG. 4

FIG. 5

FIG. 1 is a perspective view from the front and one side of the pneumatic sander;

FIG. 2 is a side elevational view;

FIG. 3 is a front elevational view;

FIG. 4 is a rear elevational view; and

FIG. 5 is a top plan view.

The undisclosed side of the pneumatic sander is the same in appearance as the side shown.

I claim:

The ornamental design for a pneumatic sander, substantially as shown and described.
